UNITED STATES PATENT OFFICE.

ALONZO J. SIMMONS, OF LOS ANGELES, CALIFORNIA.

PROCESS OF TREATING WATER

No. 867,313.

Specification of Letters Patent.

Patented Oct. 1, 1907.

Application filed January 17, 1907. Serial No. 352,774.

To all whom it may concern:

Be it known that I, ALONZO J. SIMMONS, a citizen of the United States, residing at Los Angeles, in the county of Los Angeles and State of California, have 5 invented certain new and useful Improvements in Process of Treating Water, of which the following is a specification.

This invention relates to a process of treating water.

One object of the invention is to treat water adapted 10 particularly for use in the feeding of boilers and to treat the water in such manner as to prevent and remove incrustation from the boiler.

One object of the invention is to provide an incrustation preventive ball adapted to give off certain 15 chemicals to the water in its passage to the boiler.

Another object resides in mixing chemicals and water under a whirling or centrifugal action so that chemicals and water may be thoroughly commingled prior to their passage into the boiler.

20 In carrying out my invention I may employ apparatus of different types, but in order to illustrate my invention, I show in the accompanying drawing one form of apparatus preferable under certain conditions, to wit:-

25 Figure 1 is a side elevation of the apparatus; Fig. 2 is a horizontal sectional view thereof; Fig. 3 is a transverse, vertical, sectional view of the mixing chamber; Fig. 4 is a sectional view of one form of incrustation preventive ball; and Fig. 5 is a sectional view of another 30 incrustation destroyer and preventive ball provided with numerous perforations and also showing a shield used when filling the ball with chemicals. Fig. 6 is a sectional view of another form of incrustation preventive body.

35 Referring now more particularly to the accompanying drawings, the reference character 1 indicates a pump of any suitable variety provided with an inlet pipe 2 leading from any suitable source and an outlet 3 connecting with the neck 4 of the mixing chamber 5 and 40 secured thereto in any suitable manner, the mixing chamber 5 communicating with the boiler 6 by way of the pipe 7.

The mixing chamber 5 is preferably circular in form, although it may be of any other shape, and is provided 45 with inner and outer walls 8 and 9, respectively, to form a race-way 10 for the guidance of the balls 11 whirled continuously through the race-way by the water under pressure from said pump or other source. Thus it will be understood that the water and balls 50 travel rapidly through the race-way, and, in operation it will be seen that part of the water in its whirl through the race-way falls behind the balls 11 and passes through the V-shaped or other shaped slot 12 and into the pocket 13 to the boiler by way of the aforesaid boiler connect- 55 ing pipe 7.

The water fed into the boiler by my improved apparatus is sometimes heavily charged with impurities, but be that as it may, I have found that by using certain chemicals the water may be so treated as to overcome the formation of incrustation or other scale upon the 60 interior of the boiler. I have also found that my invention will satisfactorily remove from boilers any incrustation or scale formed thereupon prior to the use of my apparatus. To accomplish such results the chemicals should be thoroughly intermingled with the water 65 and to insure this thorough intermingling of the chemicals and water I form the balls 11 hollow that they may be adapted to carry the chemicals, and I provide each ball with a perforation 14 through which chemicals may be inserted and through which the chemicals may be 70 discharged from the ball due to the centrifugal action of the balls in operation.

In one embodiment of my invention, I employ a composition consisting of hemlock extract and soda-ash with or without water. These chemicals are thoroughly 75 mixed with the water and in a semi-liquid or paste state; the composition thus compounded is inserted into the ball 11 through the perforation 14 and allowed to dry and harden. When the balls are ready for use, that is, after the compound has hardened by heating 80 them or in any other suitable manner, the balls are inserted in the mixing chamber 5 through the opening 15 which is normally closed by the cap 16. The water whirling the balls around the race-way of the mixing chamber causes the centrifugal action of the balls to 85 slowly give out the chemicals contained therein, the water in its passage through the race way of course entering the opening 14 and softening the hardened composition within the balls. The openings 14 are of small 90 size to permit a slow discharge of the chemicals.

I do not limit myself to the nature of chemicals employed, for in addition to the above mentioned compound, I might employ bicarbonate of soda, Glauber's salt, sal-soda, common salt and potash; or red lead, linseed oil and coal tar; or I might employ silica sand, 95 carbonate soda-ash and Irish moss with or without water; or I might employ graphite and tannic acid with or without water. It will thus be seen that I am not limiting myself to the chemicals used but that in this particular case I am claiming the method employed in 100 carrying out the objects of my invention.

In practice, the shells or balls are formed preferably of thin, soft metal, iron preferred, and by reason of frictional engagement of the shells or balls with the walls of the mixing chamber, small particles of iron are given 105 off from the shells or balls and taken up by the water to intermingle with the chemicals discharged from the balls, although, of course, the above mentioned separate sets of chemicals combined in the manner stated will effect the desired results.

If preferred, I might form a ball composed of any one of the above or other compounds in combination with small particles of iron, the whole ball in time wearing away, necessitating insertion in the mixing chamber of 5 new balls. In this last compound, the ingredients might be molded, pressed or otherwise forced into intimate contact with one another to provide a comparatively hard but brittle ball *a*. Further, I might add 10 New Orleans molasses or flour or both to any one of the above compounds, especially to the last named compound.

In Fig. 5 I illustrate a chemical carrying ball 17 provided with numerous perforations 18. This ball performs the same functions set forth for the ball 11, and 15 in order to facilitate filling of the ball 17 I may employ a cup shaped support 19.

The method of carrying out the present process in connection with the apparatus shown in the accompanying drawings will be stated briefly as follows:—Water 20 under pressure is forced into the mixing chamber 5 where it is whirled around in the chamber to move the balls rapidly therethrough, and to cause the balls to give off such proportions of chemicals to intermingle with the water passing through the pipe 7 into the 25 boiler 6 to positively prevent or remove incrustation formed upon the walls of the boiler.

What is claimed is:—

1. The herein described process of treating water which consists in whirling a chemical laden body with the water 30 under the influence of the latter to disintegrate the body in the presence of the water.
2. The herein described process of treating water which consists in whirling chemical laden balls under the moving influence of the water.
3. The herein described process of treating water which 35 consists in subjecting chemical laden balls to a whirling action under the moving influence of the water.
4. The herein described process of treating water which consists in subjecting water under pressure to the action 40 of chemical-laden balls.
5. The herein described process which consists in whirling a chemical laden body bodily with the water over the same course to disintegrate the body in the presence of the water, for the purposes set forth.
- 45 6. The herein described process which consists in mov-

ing a chemical laden body bodily freely under the moving influence of the water only for the purposes set forth.

7. The herein described process which consists in causing the feed water of a boiler to travel past a freely movable chemical laden body which is movable under the moving influence of the water only and capable of disintegration during its movement to continuously present particles thereof to the water for the purposes set forth. 50

8. The herein described process which consists in moving a chemical laden body bodily over the same course 55 under the moving influence of the water only to cause disintegration of the body, for the purposes set forth.

9. The herein described process of treating water which consists in whirling a chemical laden body under the influence of the water to disintegrate the body and present 60 particles of the latter to the water.

10. The herein described process which consists in passing the feed water of a boiler through a chamber containing independent, movable chemical laden bodies to cause continuous movement of the bodies over the same course 65 under the moving influence of the water only to disintegrate the bodies in the presence of the water for the purpose set forth.

11. The herein described process which consists in subjecting a brittle chemical-laden body to unrestricted movement within a chamber under the moving influence of the water only to disintegrate the body in the presence of the water for the purpose set forth. 70

12. The herein described process of treating water which consists in whirling a chemical laden body bodily with 75 the water over the same course to disintegrate the body in the presence of the latter.

13. The herein described process of treating water which consists in subjecting the water to the action of a chemical laden body having unrestricted movement in a fixed 80 chamber.

14. The herein described process of treating water which consists in subjecting the water to the action of a chemical laden body having unrestricted movement in a fixed chamber to frictionally reduce the body to small particles 85 for the purposes set forth.

15. The herein described process of treating water which consists in subjecting the water to the action of a chemical laden body having unrestricted movement in a fixed chamber to frictionally reduce the body to small particles 90 to flow with the water from the chamber.

In testimony whereof I affix my signature, in presence of two witnesses,

A. J. SIMMONS.
